UNITED STATES PATENT OFFICE

129,975

DESIGN FOR A TEXTILE FABRIC

Marcel Christen, New York, N. Y.

Application September 12, 1941, Serial No. 103,309

Term of patent 3½ years

To all whom it may concern:

Be it known that I, Marcel Christen a citizen of the United States of America, residing, in New York city, county of New York, and State of New York, have invented a new, original, and ornamental Design for a Textile Fabric, of which the following is a specification, reference being had to the accompanying drawings, forming part thereof, wherein:

I claim:

The ornamental design for a textile fabric, substantially as shown, and described.

MARCEL CHRISTEN.
